(57) **CLAIM**

The ornamental design for a multifunctional charging cable with hub, as shown and described.

DESCRIPTION

FIG. 1 is a first perspective view of a multifunctional charging cable with hub showing my new design.

FIG. 2 is a front view thereof.

FIG. 3 is a rear view thereof.

FIG. 4 is a left side view thereof.

FIG. 5 is a right side view thereof.

FIG. 6 is a top view thereof, shown enlarged in scale.

FIG. 7 is a bottom view thereof, shown enlarged in scale; and,

FIG. 8 is another perspective view thereof.

The broken lines in the drawings depict portions of the multifunctional charging cable with hub that form no part of the claimed design. The data cable is shown with a symbolic break in its length. The appearance of any portion of the article between the break lines forms no part of the claimed design.
